UNITED STATES PATENT OFFICE.

JOHN E. BOSSINGHAM, OF CANTON, OHIO.

ANNEALING-BOX BOTTOM.

1,105,059.

Specification of Letters Patent. Patented July 28, 1914.

Application filed December 4, 1911. Serial No. 629,196.

To all whom it may concern:

Be it known that I, JOHN E. BOSSINGHAM, a citizen of the United States, residing at Canton, in the county of Stark and State of Ohio, have invented a new and useful Annealing-Box Bottom, of which the following is a specification.

This invention relates to improvements in bottoms or bed-plates for annealing boxes for use in annealing furnaces, and especially to a form of such bottoms or bed-plates exemplified by the construction hereinafter described, and particularly pointed out in the claims.

The objects of the invention are to generally improve devices of the character mentioned, to provide an annealing box bottom adapted to permit heat to penetrate into the interior of said box through the bottom as well as through the sides, ends and top, to provide a light, conveniently handled bottom which will be strong and not subject to injurious warping, and to provide for the convenient handling of the assembled box and bottom when inserting same into the furnace or withdrawing them therefrom.

These objects, together with other objects readily apparent to those skilled in the art, may be attained by the construction illustrated in the accompanying drawings, although the invention may be embodied in other forms, the construction illustrated being chosen by way of example.

In the drawings Figure 1 is a perspective view of the closing member of a bottom embodying my invention, parts being broken away. Fig. 2 is a fragmentary vertical sectional view of the closing member taken at one end of the same on the line 2-2 of Fig. 3. Fig. 3 is a vertical transverse sectional view of the closing member illustrated in Fig. 1 with a fragmentary sectional view of an annealing box arranged thereon. Fig. 4 is a perspective view of the supporting member of the bottom. Fig. 5 is a fragmentary perspective of one corner of the supporting member as viewed from below. Fig. 6 is a vertical transverse sectional view through both members of the bottom in assembled position.

Throughout the several views similar reference numerals indicate similar parts.

An annealing box bottom embodying my invention comprises both a closing member and a supporting member, preferably made separable from each other. The closing

member is generally formed of a main frame, supports, and arch-formed sections connected to said frame and supports. In the construction disclosed in the drawings a channel forms the outer frame and is arranged to constitute the side frame portions 1 and the end frame portions 2. It will be noted that the flanges of the channel are inwardly disposed, and it is preferable that the channel be not entirely cut at the corners, but that the flanges be merely notched and the web bent, so that the main frame may be thus made strong and of few parts. Extending across from side to side or end to end of said main frame are spaced, intermediate supports such as the I-beams 3 shown in the drawings extending from one end to the other and fastened to said ends in any substantial, mechanical manner. This may be accomplished by cutting away the flanges of the I-beams and letting the projecting web thereof in between the flanges of the channel, as shown in Fig. 2.

The sections 4 are preferably made of metallic plates, arched in cross section, having downwardly disposed edges at both sides and ends fastened to the webs of the supports 3 and to the main frame, as by the rivets 5. It will be noted that the top and bottom flanges of the I-beams 3 are substantially in the same planes with the top and bottom flanges of the channel forming the main frame.

For the purpose of providing a suitable surface on which to arrange the sheets or other material to be annealed, the removable plate 6 is provided, which preferably consists of a plate of material laid on top of the upper flanges of the main frame and I-beams 3. On this removable plate the material to be annealed may be placed and the annealing box, of any suitable construction, may be set down upon the plate 6 and over said material. Such a box is indicated by the numeral 7 in the drawings.

Extending entirely around the main frame is the reinforcing bar 8 which consists of a band or plate of material somewhat wider than the web of the channel of which the main frame is constructed, said bar 8 being riveted to the side portions 1 and end portions 2 of said main frame with the lower edge of said bar substantially in line with the lower flange of said portions, and the upper edge of said bar projecting sufficiently above the upper flange of said frame portions to

constitute a retaining flange 9 for the sand used in sealing the box to the closing member. It is preferable that the bar 8 be merely bent at the corners so that said bar may be made in few parts. It is also preferable that any joints in said bar be arranged at points where there are no joints of the main frame. In the drawings it will be noted that the joints of the main frame are at the ends 10 and the joints of the reinforcing bar are at the sides of the structure.

The supporting member is preferably formed of a single casting and comprises longitudinal tubular portions 10 and transverse tubular portions 11 intersecting the portions 10. Both longitudinal and transverse portions have free extended ends provided with integral, upwardly extending retaining lugs 12. Formed integrally with 20 the cylindrical walls of each portion 10 is the top supporting flange 13 and each portion 11 is similarly provided with the similar integral flange 14. On the lower side of each portion 11 is an integral flange 15, extending 25 from end to end of said portion. Formed integrally with the portions 10, on the under side thereof, are the ball-race flanges 16 constituting downwardly open inverted V-shaped run-ways adapted to receive the 30 weight-carrying balls of usual construction upon which the annealing box bottoms may be moved into or out of the furnace. It will be noted that the side walls of said run-ways extend downwardly beyond the cylindrical 35 walls of the portions 10, and interrupt the flanges 15 on the portions 11, as clearly shown in Figs. 5 and 6. From an inspection of said figures it will be seen that the walls of the run-ways 16 together with the cylindrical walls of the portions 10 and the flanges 3 combine to form a strongly braced 40 structure adapted to carry a great amount of weight.

When the closing member hereinbefore 45 described is arranged upon the supporting member as shown in Fig. 6, the flanges 13 and 14 receive the main frame and I-beams of the closing member, while the lugs 12 retain the closing member in proper position 50 upon the supporting member, as will be readily understood. The longitudinal and transverse portions of the supporting member forming an open or skeleton structure, the heat of the furnace is permitted to come 55 into direct contact with the under side of the closing member and to have access to every portion of said under side. By reason of this construction the heat will be enabled to penetrate through sections 4 and 60 plate 6 into the interior of the box and the material to be annealed arranged therein with substantially the same readiness as it penetrates the side, end and top walls of the box itself. This being true less time is required for bringing the material to be an-

nealed up to the necessary temperature thus effecting a saving of time and heat and making it unnecessary to subject the box and its bottom to such a high degree of heat or for such a length of time as would otherwise be necessary in order that the material to be annealed shall receive the necessary treatment.

The tubular construction of the supporting member permits rapid and uniform heating thereof and does away, to a large extent, with the injury which would otherwise result to such a structure by reason of the repeated subjection of such member to intense heat. The uniform heating of said member 75 by reason of its tubular construction and the prevention of undue warping adds greatly to the life and usefulness of said member. Attention should also be called to the fact that by reason of the arched construction of 80 the sections 4, they are consequently free to expand and contract without materially affecting the closing member in general, does away with injurious warping of said closing member and adds greatly to its life and 85 usefulness. It will be understood that said sections being upwardly arched, upon expanding, are merely raised slightly farther in arched form, thus tending to maintain their proper shape and causing no unusual or 90 unnecessary strain upon the frame or supporting portions of the bottom.

I claim:—

1. An annealing box bottom comprising, a built-up closing member and a supporting 100 member formed of integral, intersecting, tubular portions.

2. In an annealing box bottom, a closing member comprising a main frame formed of channel-shaped portions arranged with the 105 flanges thereof inwardly turned, I-beam supports extending across said main frame and connected thereto, and arch-formed sections connected to said main frame and supports.

3. In an annealing box bottom, a supporting member formed of intersecting tubular portions constituting a skeleton structure.

4. In an annealing box bottom, a supporting member comprising integral, intersecting tubular portions provided with integral top supporting flanges extending upwardly from said portions.

5. In an annealing box bottom, a supporting member made of a single casting comprising longitudinal tubular portions and transverse tubular portions intersecting said longitudinal portions, both longitudinal and transverse portions provided with integral flanges extending upwardly along their upper sides, said transverse portions provided with integral flanges extended downwardly from their under sides, and said longitudinal portions provided with downwardly open ball run-ways formed from integral flanges 125 130 135

united at points within the circumferences of said longitudinal portions and having external portions extending downwardly beyond the lower sides of said longitudinal portions and interrupting the flanges on the lower sides of said transverse portions.

In testimony that I claim the above, I

have hereunto subscribed my name in the presence of two witnesses.

JOHN E. BOSSINGHAM.
